UNITED STATES PATENT OFFICE.

JAMES NOBLE EDELIN, OF WASHINGTON, DISTRICT OF COLUMBIA, ASSIGNOR TO NOVELTIES MFG.-SALES CORPORATION, OF WASHINGTON, DISTRICT OF COLUMBIA, A CORPORATION OF DELAWARE.

COIN-HOLDING DEVICE.

Application filed December 19, 1921. Serial No. 523,518.

To all whom it may concern:

Be it known that I, JAMES NOBLE EDELIN, a citizen of the United States, residing at Washington, District of Columbia, have 5 invented certain new and useful Improvements in Coin-Holding Devices; and I do hereby declare the following to be a full, clear, and exact description of the invention, such as will enable others skilled in 10 the art to which it appertains to make and use the same.

This invention relates to certain improvements in coin holding devices and the like, and particularly to a simple and convenient holder for small coins and street car fare tokens.

The principal object of the invention is to provide a simple and inexpensive device of the character indicated, designed and constructed to receive and hold a certain number of coins or tokens in such a manner as to be dispensed therefrom as desired upon a simple manipulation of the device, said device being of suitable shape and size to be 20 conveniently carried in the pocket, purse or hand-bag, or suspended from a key ring or the like.

Another object of the invention is the provision of a device of this type preferably stamped and formed from a single strip of suitable material so that said device will hold, in superimposed position a double layer of coins or tokens said layers being separated by the main body portion 30 of the device or, in other words, a row of coins or tokens will be disposed on opposite sides of said device.

A further object is to construct the holder in as simple and inexpensive a manner as 40 possible, eliminating all supplementary or auxiliary means for retaining the coins or tokens in the holder, said retaining means in the present construction being formed as an integral part of the device in a manner 45 as will hereinafter appear.

The preferred embodiment of the invention is illustrated in the accompanying drawings in which:

Figure 1 shows in perspective the improved device.

Figure 2 is an end view thereof.

Figure 3, a transverse sectional view.

Referring to the drawing in detail and particularly Figure 1, the device which is

substantially flat comprises a main body 55 portion 1 provided along its longitudinal edges with a series of oppositely bent in-turned clips or the like 2, the inturned portions of said clips being properly spaced from the main body portion 1 to permit the 60 insertion therebetween of a coin, token or the like, of the proper denomination.

It will be noted that the alternate clips 2 are bent in opposite directions and overlie the opposite spaces of the main body portion 1, thereby providing, as it were, superimposed guide-ways for receiving two rows of successively positioned coins or tokens, which tokens are inserted from one end of the device.

One or both ends of the device are provided with oppositely curved resilient portions 3 and 4, said resilient portions being formed by extensions of the main body portion 1. As illustrated, this construction is 75 only applied to one end of the device the other end of the device being provided with a ring or similar arrangement 5 for suspending the same from a key ring or the like. It is also within the scope of the invention to replace the ring 5 with an integrally formed clip or projection where it is not desired to use the suspending means. Both the ring and clip constructions, as preferred, will prevent the displacement of 80 the coins or tokens from this end of the device, or as hereinbefore stated, if both ends of the device are provided with the oppositely bent portions 3 and 4, these portions will perform a similar function and in addition permit the insertion and withdrawal 85 of the coins or tokens from either end of the holder.

It is believed from the foregoing description that the operation or manipulation of 95 the device will be perfectly obvious. The outwardly bent portions 3 and 4 being of a resilient character, will permit, upon exerting the necessary pressure, the coins to be successively inserted in the guide-ways between the main body portion 1 and the bent 100 clips 2, said coins to be withdrawn in a similar manner.

By simply splitting the end of the main body portion 1 and slightly bending in opposite directions, the portions 3 and 4 formed thereby, a simple and ingenious means is provided for normally maintain-

ing the coins or tokens within the guideways and also permitting, upon the proper manipulation, their withdrawal therefrom.

The whole device can be stamped from a single strip of sheet metal or the like, the opposite longitudinal edges of the blank being cut or provided with the necessary slits to produce the inturned clips 2 in the manner as hereinbefore specified.

10 From the foregoing description it will be apparent that the complete coin holder can be constructed by a simple operation and from a single blank whereby the same can be cheaply and expeditiously produced.

15 What I claim is:

1. A coin holding device, comprising a substantially flat main body portion having a series of oppositely bent clips arranged along each longitudinal edge thereof, forming a pair of guide-ways adapted to receive successively positioned coins or tokens and means formed integrally with said body portion for normally maintaining said coins within each guide-way.

25 2. A coin holding device, comprising a substantially flat main body portion having a series of oppositely bent inturned clips arranged along each longitudinal edge there-

of, forming superimposed guideways adapted to receive successively positioned coins or tokens and resilient, oppositely curved, integral extensions formed on the end of said body portion for normally maintaining said coins within each guide-way.

3. A disk holder comprising an elongated plate having substantially parallel sides, with a series of clips stamped out of said sides and bent over to form a channel for the disks, a resilient inclined holding lip provided at one end of said plate, and a supporting ring serving as a stop and swiveled near the end of said plate opposite said lips, substantially as described.

4. A disk holder comprising an elongated plate having substantially parallel sides, with a series of reversely disposed clips stamped out of said sides and bent over to form a pair of oppositely disposed channels for the disks, a pair of reversely disposed resilient lips provided at one end of said plate, and a stop projecting into both of said channels provided near the other end of said plate, substantially as described.

In testimony whereof I affix my signature.

JAMES NOBLE EDELIN.
